ATTORNEY:

UNITED STATES PATENT OFFICE.

CHARLES E. HANSEN, OF PROVIDENCE, RHODE ISLAND.

DESIGN FOR AN EMBLEM.

No. 39,723.

Specification for Design.

Patented Dec. 29, 1908.

Application filed October 5, 1908. Serial No. 456,342. Term of patent 14 years.

To all whom it may concern:

Be it known that I, CHARLES E. HANSEN, a citizen of the United States, residing at Providence, in the county of Providence and State of Rhode Island, have invented a new, original, and ornamental Design for an Emblem, reference being had to the accompanying drawing.

The figure in the drawing represents the face view or obverse side of an emblem, showing my design.

I claim—

The ornamental design for an emblem, as shown.

CHARLES E. HANSEN.

Witnesses:

ADA E. HAGERTY,
J. A. MILLER.
